UNITED STATES PATENT OFFICE.

THOMAS J. NEWLYN, OF EL PASO, TEXAS.

DESIGN FOR A FACE-POWDER BOX.

Application filed July 5, 1922. Serial No. 2,971. Term of patent 7 years.

To all whom it may concern:

Be it known that I, THOMAS J. NEWLYN, a citizen of the United States, residing at El Paso, in the county of El Paso and State of Texas, have invented a new, original, and ornamental Design for a Face-Powder Box, of which the following is a specification, reference being had to the accompanying drawings, forming a part thereof.

I claim:—

The ornamental design for a face powder box as shown.

THOMAS J. NEWLYN.
